UNITED STATES PATENT OFFICE.

JAMES P. O'SHEA, OF NEW YORK, N. Y., ASSIGNOR TO COOPER HEWITT ELECTRIC COMPANY, A CORPORATION OF NEW JERSEY.

MERCURY SWITCH.

Application filed November 21, 1923. Serial No. 675,981.

My present invention relates to switching means for electrical apparatus which are or may be subjected to rectilinear or other motion. It relates particularly to switching means for electrically heated flatirons and the arrangement thereof in the iron, but is applicable in the arts generally in the use of the fluid type or mercury switch in apparatus subjected to motion or in which the fluid switch is subjected to motion.

Considerable trouble is experienced as a result of undesired movement of the fluid of the switch from the motion of the apparatus in which it is used resulting in the intermittent opening and closing of the switch.

I also find it desirable that means be provided for opening a switch in a flatiron automatically when the iron is not in actual use in the ironing operation.

It is the object of my invention to provide an arrangement of liquid switches in moving apparatus or in apparatus subjected to motion such that will preclude the undesired interruption of the circuit due to the flow of the liquid of the switch resulting from the motion of the apparatus in use.

Another object of my invention is to provide means for automatically opening a flatiron switch when the flatiron is not held closed by pressure of the hand of the operator of the iron.

Another object of my invention is to provide means for keeping the switch of an electric flatiron closed for a definite interval after pressure has been released from the handle.

I find that by mounting a fluid switch which is subjected to motion in the use of the apparatus to which it is applied transversely with respect to the average path of said movement that the movement of such liquid is reduced to a minimum for such a switch and that for most uses such for example as in a flatiron that such reduced motion will not result in the undesired opening of the switch. In such a flatiron I find that the best place to mount the switch is the middle or rear thereof, or at some point therebetween.

I also find that by making one of the straps connecting the handle of the iron to the iron in the form of a spring and making the other of such straps with a loose connection between it and the iron to allow movement thereof by or against the pressure of said spring that I can utilize first said strap

to move the switch of the iron to open it through a connection between the switch and the handle as, for instance, between the switch and the lower end of said second strap.

In the accompanying drawings which form a part of this specification and in which like characters refer to like parts I have shown in:

Fig. 1, plan view in part section of an electrically heated flatiron showing a mercury switch in the circuit thereof mounted transversely of the axis of the iron, and at the rear thereof.

Fig. 2, a vertical sectional view through line 2-2 of Figure 1 looking in the direction of the arrow showing a mercury switch mounted in an electric flatiron and in the closed position.

Fig. 3, a view similar to Figure 2 showing the switch in the circuit opening position.

Fig. 4 is a longitudinal elevation view of a flatiron embodying the switch opening handle feature showing in dotted lines the open switch position of the handle and rear strap.

Fig. 5, is a cross-sectional view of the flatiron of Figure 4 and showing the switch in the closed position.

Fig. 6, is a cross-sectional view similar to that in Figure 5 but with the switch closed.

Fig. 7, is a cross-sectional view of a flatiron having a mercury switch in which is a flow restricting constriction, the switch as shown being in the circuit opening position and the mercury therein not having all flowed to the lower end thereof.

In Figures 1 to 3 of the drawings the mercury switch 1 connected in series with resistance heater 3 of sadiron 2 is mounted transversely of the axis of the sadiron and at the rear thereof and is held to the casing 4 of the iron by means of strap 5 around the body of the switch which has a pivotal connection 6 with the lug 7 mounted inside the top of said casing. Another strap 8 around one end of the body of the switch is pivotally connected to the handle 9 by means of the rod 10 which extends through the casing 4 and serves for the movement of the switch for the opening and closing thereof for the energization and deenergization of the heating element. One end of the switch 1 is connected through a flexible lead 13 to

the connection stud 11 and the other end is connected to one end of the resistance heater 3, the other end of said heater being connected to the connection stud 12.

5 It is of course understood that by tilting the iron either backward, forward, or to one side that the circuit through the switch and so through the heating element can be opened by the movement of the mercury 10 through such change of position instead of moving the switch by means of handle 9.

In the Figures 5 and 6 of the drawings the mercury switch 1 connected with resistance heater 3 of flatiron 2 is mounted transversely of the axis of the sadiron and at the rear thereof and is held to the casing 4 of the iron by means of strap 5 around the body of the switch which has a pivotal connection 6 with the lug 7 mounted inside the top of 20 said casing. Another strap 8 around the body of the switch is pivotally connected to the strap 20 of the handle by means of the rod 21 which extends through the casing 4 and is riveted to the lower end of said strap 25 20. The handle 15 of the iron is held thereto by means of straps 20 and 16, the latter of which has its lower end fixed to the casing 4 and is formed as a spring which tends to move handle 15 away from the iron. The 30 rod 21 has fixed to it the movement limiting flange 17 which allows of sufficient movement of the handle and therethrough of switch 1 to cause the mercury therein to flow to open the circuit therethrough when spring 35 strap 16 moves them. The washer 18 is of some comparatively soft material and is interposed between casing 4 and the lower end of strap 20 to prevent excessive wear therebetween. The closing of switch 1 for 40 the energization of the heating element is effected by pressure exerted through the hand of operator of the iron in the use thereof. One end of the switch 1 is connected through a flexible lead 13 to the connection 45 stud 12 and the other end is connected to one end of the resistance heater 3, the other end of said heater being connected to the connection stud 12.

In the use of the sadiron the motion thereof in ironing being for the most part longitudinal there will be little tendency of the mercury in switch 1 to move to open the circuit therethrough, and the switch being placed at or near the rear of the iron lateral movement of the point of the iron for ironing seams, tucks, etc., will have little tendency to cause movement of the mercury of the switch to open the circuit therethrough. For some purposes I find that it 50 is best to mount the fluid switch not exactly at right angles across the axis of the iron but at an angle to suit the average path of the iron in such use, as for instance for some purposes a right handed person moves the iron in an average path which is at an angle 55

to the right or clockwise from the axis of the iron. I accordingly suit the location of the switch to the conditions of the particular or average use to which it is subjected. However, for most practical use I mount 70 the switch substantially at right angles to the axis of the iron.

In Figure 7 is shown a mercury switch 22 mounted in the flatiron similarly to that in Figures 5 and 6 but in this case the switch 75 has a constriction 23 between the terminals thereof to form a flow restricting baffle in the path of the mercury whereby the switch is still closed for a space of time if it is moved into the open circuit position. This restriction is formed by indenting the tube of the switch body from the upper side thereof whereby a direct path of small cross section is provided between the two ends of the switch. The same results are obtained 85 by connecting the two bulbous ends of the switch by a capillary tube of suitable cross section.

In the operation of this form of my invention when the flatiron is in use and is set aside for a short while to arrange the articles being ironed, the current will not be intermittently turned on and off because the mercury path between the terminals of the switch will not be immediately broken when pressure is released from the handle of the iron and spring 90 16 moves the switch 22 into the open circuit position, the timing of the mercury flow being such as to allow for such arrangements 95 between the time the pressure is released 100 from the handle and the time the pressure is resumed for most purposes.

Likewise the timing of mercury flow in the switch for some purposes is made so as to take about the same time as is required to bring 105 the iron from the cold condition to the hot when current is first turned on so that in starting the use thereof the handle is first depressed to close the circuit through the switch and then it may be released as the iron 110 will have become heated before the mercury flows to open the circuit through the switch and in such case means comprising a tube of large cross section are provided to allow the mercury to flow quickly from the open circuit position into the closed circuit position. For the same purpose in some cases I use a 115 mercury switch of the ordinary type with means such as a timed spring release interposed between the operating spring strap 16 and said switch to delay the opening thereof 120 for a predetermined time after pressure is released from handle 15.

I claim as my invention:

1. In an electric flatiron, in combination, 125 a body having an electric heating element and a pivotally mounted switch for said element therein, a handle gripping member for said iron, and two strap connections between said handle and said iron one of 130

which has a moving connection to said iron and a pivotal connection to said switch and the other of said straps being in the form of a spring tending to move and hold said switch in the open circuit position.

2. In an electric flatiron, in combination, a body having an electric heating element and a pivotally mounted mercury switch for said element therein, a handle gripping a member for said iron, and two strap connections between said handle and said iron one

of which has a moving connection to said iron and a pivotal connection to said mercury switch and the other of said straps being in the form of a spring tending to move and hold said mercury switch in the open circuit position.

Signed at Hoboken in the county of Hudson and State of New Jersey this 19th day of November, A. D. 1923.

JAMES P. O'SHEA.
